CALL REGISTER

Original Filed Dec. 7, 1925 3 Sheets-Sheet 3

UNITED STATES PATENT OFFICE

ARTHUR PENTECOST, OF MONTCLAIR, NEW JERSEY

CALL REGISTER

Original application filed December 7, 1925, Serial No. 73,672. Divided and this application filed July 19, 1927. Serial No. 206,812.

This invention appertains to improvements in call registers and devices for registering calls.

This application is a division of my pending application Serial No. 73,672, filed December 7, 1925.

In said application I have claimed a device for providing permanent records of the calls made, and means whereby the call register cannot be tampered with from the interior of the building to which it is attached.

In the present application the invention deals with a means for preventing tampering with the call register from the exterior and more specifically comprises in combination with the register means for giving a signal either visible or audible when the register is manipulated. The signal means of the present invention is embodied in a preferred form which is carried out substantially as described in the following specification of which the drawings form a part and wherein like numbers refer to like parts throughout.

In the drawings,

Figure 1 is a side elevation, partly broken away, of the device embodying my invention with the parts in normal positions.

Figure 2 is the same as Fig. 1 except that the parts are in the positions called for by the handle having been operated.

Figure 3 is a front elevation of Figure 1 with the cover broken away.

Figure 4 is an elevation of the interior end of Figure 1.

Figure 5 is a part front elevation of Figure 1 showing the handle, endorsing aperture and the illuminating or visual signal means.

Figure 6 is a top plan view of the interior end of Figure 1.

Figure 7 is a section through A—A of Figure 2.

Figure 8 is a modification of the perforating means.

In Figure 1, the outer and inner surfaces of a wall are represented by 1 and 2 respectively. Attached to the face of surface 1 is a plate 3 and hinged to this plate as at 4 is a cover 5 of the contour shown and which again meets the plate 3 in a locking device as at 6 which

I show in this instance as a hasp and staple arrangement adapted to take a padlock although it is obvious that any other suitable locking device would do equally well; the object being to prevent access to the parts by removing cover 5. In the lower part of cover 5 is a storage for a supply or roll of paper or other material 7 which I also designate as the operation indicator or record tape. This record tape may be mounted upon stubs 8 and 9 (Fig. 3) which in turn are respectively supported by one side of the cover 5 and the bent piece 10 affixed to the other side of the cover and having sufficient resiliency to allow replacement of the record tape supply by 60 springing it enough to clear the stubs 8 and 9. Above the record storage is a shaft 11 upon which is a platen 12 and immediately above this first shaft is a second one 13 upon which is another platen 14. This platen 14 has a 70 degree of movement because of the slots 15 in which the shaft 13 is mounted so that under the pressure of the spring 16 on the shaft 13 the platen 14 is always in contact with the platen 12. Loosely mounted upon the shaft 11 75 is the handle or actuator 17 which carries the pawl 18 pivoted at 19 and which coacts with the ratchet 20 which is arranged to rotate the platen 12 in one direction; opposite rotation of the ratchet 20 being prevented by 80 the spring stop 20^a fixed to the plate 3. This pawl 18 is held in contact with the ratchet 20 by the spring 21 affixed to the handle 17 as at 22 and the handle 17 is normally held upwards by the spring 23 attached to the handle 85 as at 24 and to the cover as at 25. Extending between the outer faces of the surfaces 1 and 2 is an enclosed passage or tape guiding means, 26 which is shown in cross section in Fig. 7. This enclosed passage is held in position by 90 suitable means such as flanges extending from plate 3 or surface 1 and plate 27 or surface 2 although any other means may be used which will hold this tape guide 26 in proper position. Pivoted to one side of this passage 26 is a bar 95 28 adapted to turn on the pivot 29. This bar extends past the surfaces 1 and 2 and its outer end is reduced to form a projection 30 (see Figs. 1 and 8) which fits in a cut 31 of the actuator 17. On the same end of the bar 28 and 100

adjacent to the projection 30 is a trip 32 pivoted at 33 and which is under the action of the spring 34 acting between the trip and the bar 28. On the actuator 17 is a block 35 located so as to engage with a shoulder 36 on the trip 32 and extending from the cover 5 is a pin 37 which acts as a throw off for the trip. The inner end of the bar 28 carries a punch holder 38 held in place by the set screw 39 and the punch 40 is retained in the holder by the screw 41, the whole forming perforating or visible recording means. The punch holder 38 has downwardly projecting portions 42 over which is the compression spring 43 acting against the holder 38 and the lip 44 of the plate 45. This plate 45 is placed upon and fixed to the plate 27 (Fig. 4) and in addition to the lip 44, it has an upward extension 46 which serves as a guide for the bar 28 (Fig. 6) and also on this same plate 45 is an outwardly extending portion 47 having an edge 48 to form cutting means and an opening 49 through which the punch 40 passes in the punching operation. Above plate 45 and similarly fixed to plate 27 is plate 50, a portion of which is bent as shown at 51 and this bent portion has an aperture 52 for a use to appear hereafter. In Fig. 5, the cover 5 is shown in part and in which there is a slot 53 through which the actuator 17 extends and there is also in this cover 5 an aperture 55 which registers with the platen 12 (Fig. 1). To block this aperture 55 when the device is in normal position, I provide a shutter or closure 56 which is faced to and moves with the actuator as shown in Fig. 1 so that normally this shutter prevents access to the platen 12 and no such access is possible unless and until the shutter 56 is taken from in front of the aperture 55 by movement of the actuator 17, such action being shown in Fig. 2. Furthermore, I provide signal means, both audible and visual, as follows. Within the cover 5 and attached to the plate 3 are two spring conducting strips 57 and 58 separated by the insulation 59 and 60 and having terminals such as at 61 and 62 from which lead the wires 63 and 64. On the upper end of the conducting strip 57 is a cam or roller 65 and a contact point 66 while the upper end of strip 58 has a contact point 67. The contact points 66 and 67 are normally separated while the roller 65 is preferably in continuous contact with the cam surface 68 of the actuator 17. The wires 63 and 64 lead to a sounding device such as a bell or a buzzer and a source of power as is well understood in the art. The visual signal means are illustrated by a lamp 69 fed by the wires 70 and 71 and so arranged that it projects into the hood 72 (Fig. 5) formed in the cover 5 and which has an aperture 73 to throw the light downward upon the aperture 55. The wires 70 and 71 are in the same circuit with the wires 63 and 64 so that whenever the circuit of 63 and 64 is closed by the contact

points 66 and 67 to give the audible signal, the circuit of 70 and 71 is similarly affected to light the lamp or visual signal.

In Figure 8 I show a modification of the perforating or recording means as follows. Instead of the bar 28 and its related parts, I modify the plate 45 somewhat as shown and place the punch 40 in the core of a solenoid as at 74; this solenoid having a cover 75 and the core is normally held upwards by a spring 76 acting between the core and the cover. Loosely mounted upon a pivot 77^a is a trip 77 held against the pin 78 by the spring 79 but which is free to move upward away from this pin. Arranged to coact with the trip 77 and pivoted at 80 is a contact piece 81 having a cam face 82 and a contact point 83 and adjacent to contact point 84 held in the piece 85. The wires 86 and 87 and the solenoid leads 88 and 89 serve to energize the solenoid whenever the contact 83—84 is closed and these wires may either lead to a separate source of power or may be incorporated in either or both of the signal circuits, it being understood that all of these circuits may be varied to suit conditions and that the source of power is not important except that it be adequate to the needs of the device.

In the operation of my device, the normal inoperative position is shown in Fig. 1 where the record tape 7 passes from the rear of the storage roll, forward and over the platen 12 (which may be called the registration platen), under the platen 14 (which may be called the feed platen) and thus through the closed passage 26 until it emerges through the opening between plates 47 and 51 and under the punch 40 on the interior end of the device as shown in Figs. 1 and 2. Operation occurs by movement of the actuator 17 from its normal position of Fig. 1 to any intermediate point between that and the position of Fig. 2. When the actuator is so moved, it carries with it the shutter 56 to expose the record tape 7 on the endorsing platen 12 through the aperture 55.

Also the cam surface 68 of the actuator 17 flexes the strip 57 to make contact between the points 66 and 67 to close the signal circuits whereupon the buzzer or bell will sound and the lamp 69 will light both as a signal and to illuminate the endorsing surface in the aperture 55. Both of these signals will continue in action as long as the actuator is held away from its normal position. Also as the actuator is moved, the block 35 goes upward, engages the shoulder 36 of the trip 32 and raises the bar 28 which in turn forces the perforating means downward at the interior end of the device so that the punch 40 passes through the record tape 7 and makes the permanent and visible record that the call register has been operated and a call made. By the time the perforation has been made, the trip

32 has been raised to a point where it contacts with the pin 37 whereupon the trip is moved out of engagement with the block 35. When this occurs, the spring 43 which has been compressed in the perforating operation, then restores the perforating means upwardly, and as the trip 32 is out of engagement the bar 28 resumes its normal position by turning about the pivot 29. Also in this movement of the actuator 17, the pawl 18 is pulled over the ratchet 20; this ratchet being held against movement by the stop 20^a so that the platen 12 does not move nor does the record tape 7; in other words, the feeding means just mentioned is prepared for subsequent action. Therefore, from the foregoing it will be seen that a movement of the actuator away from normal exposes varying degrees of the record tape on the registration platen in accordance with the extent of such movement, that the perforating means is actuated to make the visible and permanent record and is restored, that either or both of the audible and visual signal means are operated and that the feeding means is prepared also to act in proportion to the extent of actuator movement. When the actuator 17 has been moved as just described, and as illustrated in Fig. 2, its spring 23 is extended and when the actuator is released, this spring causes the return movement to normal; in such movement and the feeding means having been prepared, the pawl 18 causes the ratchet 20 and the platen 12 to rotate and thus feed the record tape 7 forward under the feed platen 14, through the closed passage 26 and out over the cutting edge 48 on the interior end of the device. At the same time, the shutter 56 is moving with the actuator 17 to close the aperture 55 and the roller 65 is moving from the high part of the actuator cam surface 68 to break the contact 66—67 and open the circuit of the audible and visual signal means; the bell or buzzer and the lamp 69. Consequently, as the actuator resumes its normal position of Fig. 1, the record tape with its record has been fed forward out of sight and possibility of being tampered with, the aperture over the record tape or the registration platen is closed, the signal means are disconnected and the block 35 again engages under the shoulder 36 of the trip 32 on the bar 28 and the device is in position for a subsequent operation. While the parts are in their normal position as shown in Fig. 1, the projection 30 of the bar 28 is entered in the recess 31 of the actuator 17 (see also Fig. 8) and this recess is directly above the shaft 11. This provides a locking means so that if an attempt be made to operate the perforating means in any way other than by the actuator, the bar 28 cannot move because of projection 30 being held in recess 31 and therefore the perforating means remain immovable unless legitimately operated.

The modification of Fig. 8 is shown with the parts in normal position; this modification referring only to the perforating means so that the other parts of the device remain the same. As the actuator 17 moves away from normal, the trip 77 is carried upward by the pin 78 and rides over the cam surface 82 of the piece 81 which rocks this piece about its pivot 80 and makes contact between the points 83 and 84 to close the circuit including wires 86—87 and 88—89. This energizes the solenoid 74 to cause the punch 40 to pass through the record tape 7. The action is only momentary for as the trip 77 passes the cam face 82, the piece 81 recovers to normal position under the action of the spring 81^a and breaks the contact between the points 84 and 83 so that the solenoid becomes inactive and the punch 40 is withdrawn upwards by the spring 76. As the actuator 17 moves backward to its normal position in a counter-clockwise direction, the trip 77 rides down over the cam surface 82 of the piece 81 against the tension of the spring 79 until the two are clear whereupon the spring 79 returns the trip 77 to its position against the pin 78.

From the foregoing disclosure of my invention, many advantages will be found among which may be mentioned that every operation of the handle gives an unalterable visible record of the call which, together with whatever message is endorsed upon the record tape, immediately passes beyond the control of the operator and is concealed from him so that it cannot again be reached. The extent of movement of the actuator determines the surface of tape exposed up to the full opening of the aperture in the cover so that messages of varying length may be written and also one of indefinite length by successive movement of the handle, each portion of the message so made passing out of sight of the operator. Therefore not only does each movement of the actuator perforate the tape and cause the signals to work as long as this actuator is away from its normal position but every message is held from the view and control of every one but the proper person. As a check upon calls and messages and to prevent tampering from the interior, the record tape may be cut by the edge 48 to form a zero line and one's initials or other mark may be placed on the inner end of the tape through the aperture 52 so that everything subsequent to that point can be determined with certainty as it appears on the tape with assurance that no part of the tape with its record has been removed. The continual action of the signals while the handle is held away from normal insures the operator being heard and even without a written message on the tape, the perforation registers the call and a succession of such perforations may signify the absence of any

employee left in charge. These perforations record the number of calls and their proximity to each other gives an indication of the action of the actuator a series of closely spaced perforations indicating probable partial operation by the same person while regularly spaced ones, a series of separate calls. Tampering with the perforating means is excluded because of the locking arrangements spoken of and by the cover over the solenoid in the case of electrical perforating.

I have chosen to show my invention in a preferred form merely by way of illustration and explanation. It will be obvious that many changes and variations may be made without departing from the spirit of my invention and all such changes and variations I include within the scope of my claims.

20 I claim:—

1. In a device of the class described, means forming a housing for a supply of record tape, said housing having an opening in its wall through which messages may be inscribed on the tape, means for supporting the tape in the housing in a manner to pass the tape by the opening, a lever and ratchet mechanism for feeding the tape in correspondence to the extent of the manipulations thereof, a shutter for controlling the opening in the housing and operable by the lever and ratchet mechanism in synchronism with the feeding of the tape, said shutter being reciprocated by the lever oscillations to an extent corresponding therewith, and a signal operated by the lever and ratchet mechanism and functioning at all times during the opening of the shutter.

2. In a device of the class described, means forming a housing for a supply of record tape, said housing having an opening in its wall through which messages may be inscribed on the tape, means for supporting the tape in the housing in a manner to pass the tape by the opening, a lever and ratchet mechanism for feeding the tape in correspondence to the extent of the manipulations thereof, a shutter for controlling the opening in the housing and operable by the lever and ratchet mechanism in synchronism with the feeding of the tape, said shutter being reciprocated by the lever oscillations to an extent corresponding therewith, an electric circuit, a signal in the circuit, and a switch for the circuit, said switch being controlled by the lever and in circuit closing position when the lever is in position corresponding to opening of the shutter.

3. In a machine of the character set forth, the combination of a housing formed with an aperture, a platen arranged in juxtaposition to said aperture, a record-feeding element, a shield normally interposed between said platen and said housing at said aperture, a signal, and a member movable in one direc-

tion for effecting operation of said shield and of said signal, and in the opposite direction for effecting record-feeding operation of said record-feeding element.

4. In a machine of the character set forth, 70 the combination of a housing formed with an aperture, a platen arranged in juxtaposition to said aperture, means for illuminating said platen, a record-feeding element, and a member movable in one direction for rendering said illuminating means effective and in the opposite direction for operating said record-feeding element.

5. In a machine of the character set forth, 80 the combination of a housing formed with an aperture, a rotary platen arranged in juxtaposition to said aperture, a shield normally interposed between said platen and said housing at said aperture, and a member movable in one direction for effecting movement of said shield from between said platen and said aperture and in the opposite direction for effecting movement of said platen for record-spacing.

6. In a machine of the character described, 90 the combination of a housing, means mounted in said housing for supporting and feeding a record, and means associated with said housing for guiding and supporting record material fed from said housing and including 95 an element apertured to facilitate record-end marking.

In testimony whereof, I have signed my name to this specification this 18th day of July, 1927.

ARTHUR PENTECOST.
